(57) **CLAIM**

The ornamental design for a combined hood, headlight cowling and grill for a vehicle, shown and described.

DESCRIPTION

FIG. 1 is a perspective view of a combined hood, headlight cowling and grill for a vehicle showing our new design;

FIG. 2 is a front view thereof;

FIG. 3 is a top view thereof;

FIG. 4 is a right side view thereof; and,

FIG. 5 is a left side view thereof.

The broken lines are shown for illustrative purposes only and form no part of the claimed design.
